UNITED STATES PATENT OFFICE.

HENRY A. MEYER, OF CINCINNATI, OHIO, ASSIGNOR TO THE WOLF ELECTRICAL PROMOTING COMPANY, OF CINCINNATI, OHIO, A CORPORATION OF OHIO.

CLOTH-CUTTING MACHINE.

Application filed May 24, 1920. Serial No. 383,630.

To all whom it may concern:

Be it known that I, HENRY A. MEYER, a citizen of the United States, residing at Cincinnati, in the county of Hamilton and 5 State of Ohio, have invented certain new and useful Improvements in Cloth-Cutting Machines, of which the following is a specification.

My invention relates to cloth cutting machines employing a reciprocating knife.

It is the object of my invention to provide novel protecting means for the driving means for the knife; further, to provide novel means for conducting a lubricating 15 fluid to the guide for the knife; further, to provide such means with novel viewing means for the flow of lubricating fluid; and, further, to provide novel lubricating means for a reciprocating knife, and regulating 20 means for regulating the flow of lubricating fluid located in substantially the longitudinal projection of the motor and in adjacency to the driving means for the knife.

The invention will be further readily understood from the following description and claims, and from the drawings, in which latter:

Fig. 1 is a side elevation of a cloth cutting machine, partly broken away, embodying my invention.

Fig. 2 is a front elevation of the same, partly broken away.

Fig. 3 is a vertical axial section of the same, taken on the line 3—3 of Fig. 2, the 35 rear part of the machine being removed.

Fig. 4 is a vertical cross-section of a detail of my improved device, taken on the line 4—4 of Fig. 3.

Fig. 5 is a perspective view of a detail of 40 my improved device partly broken away, showing the means for guiding, regulating and viewing the flow of lubricating fluid.

Fig. 6 is a rear elevation of the protecting reservoir.

Fig. 7 is a vertical cross-sectional detail 45 of the same, taken in the plane of the line 7—7 of Fig. 3.

Fig. 8 is a plan section of my improved device, taken on the line 8—8 of Fig. 1.

Fig. 9 is a cross-sectional detail of the 50 same, taken on the line 9—9 of Fig. 1; and,

Fig. 10 is a cross-sectional detail, taken on the line 10—10 of Fig. 1.

I have found it desirable in a machine of 55 the character mentioned to provide lubricat-

ing means whereby to impart lubricating fluid to the reciprocating knife and its guideway so as to lubricate the same. I have also found that, in providing a means of this character, it is desirable that the lubricating 60 fluid be directed to a point in close proximity to the knife. I have further found that, by providing my improved device, the range of work on a machine of this character has been materially increased. I provide means whereby the flow of lubricating 65 fluid may be regulated from a point adjacent to the point of application of the lubricating fluid, and have also provided viewing means between the regulating means and 70 the point of application of the lubricating fluid, whereby the amount of lubricating fluid applied to the knife may at all times be promptly regulated so as to cause decrease, increase, or cessation of flow of lubricating 75 fluid, immediately that requirement for change in flow of lubricating fluid is noted.

It is essential that an overflow or flooding of lubricating fluid shall not take place 80 when not desired, as otherwise the lubricating fluid, for instance oil, will communicate itself to the cloth which is being cut, which is at times extremely delicate in color and texture, and is liable to be damaged by contact of lubricating fluid therewith. Other cloths which the device is adaptable for cutting, require a substantially greater flow of 85 lubricating fluid. Some of the materials to which I have adapted the device require so 90 great a flow of lubricating fluid as to cause lubrication practically at that part of the knife which passes through the goods, so as to apply lubrication between the knife and the goods, for instance, when cutting rubberized or leatherized cloths or fabrics, such as the cloths or fabrics for automobile tops, 95 seats, and other materials.

The reciprocating knife is exemplified at 21. It reciprocates in a standard 22, the 100 standard being provided in the present exemplification with a narrow guideway 23, the walls of which guide the knife in its reciprocations. The standard rises from a usual foot-plate 24, supported on suitable 105 rollers, not shown, which has a usual cloth-lifter 25 pivoted thereto in advance thereof. The cloth-lifter and foot-plate pass under the cloth or other flexible goods, which is laid in layers one on top of the other, to 110

form a stack of layers of the flexible goods, which are simultaneously cut by the reciprocating knife along the lines of a suitable pattern, or otherwise. A suitable presser-
5 foot 27 is shown adjustable in elevation so as to coact with the upper face of the top layer of the stack of layers of flexible goods.

An electric motor 31 is exemplified as the motive power for reciprocating the knife.
10 The motor comprises a casing 32, shown as containing fields 33 and the operating shaft, shown as an armature-shaft 34, of the electric motor, the armature-shaft being journaled in the suitable bearings, one of which 15 is shown at 35. A crank 36 is fixed in suitable manner to the armature-shaft, as by means of a set-bolt 37. The crank has a crank-pin 38 thereon.

A reciprocating slide 41 reciprocates up
20 and down in guides 42, adjustably secured in suitable manner, as by set-screws 43 and clamp-screws 44 in a housing 45 having brackets 46 extending therefrom, and secured, as by screws 47, to the motor casing.
25 The motor casing is supported on the standard 22, as by providing the standard with a bracket 50, received between the brackets 46, the brackets 50 and 46 being clamped together by bolts 51 and nuts 52.

30 The slide is provided with a journal-stud 55. A pitman 56 connects the crank with the slide, the pitman having a bearing 57 about the crank-pin 38, and a bearing 58, about the journal-stud 55, the pitman being 35 suitably held in operative positions, as by washers 59, 60, and screws 61, 62, coacting respectively with the crank-pin and the journal-stud.

The reciprocating knife is exemplified as
40 secured to the reciprocating slide, as by providing the slide with a lug 65, through which a bolt 66 passes. The upper end of the knife is provided with a slot 67, forming upward extensions or fingers 68 of the knife
45 at the respective sides of the slot. The fingers are received at the respective sides of the bolt, and are clamped between the head 69 of the bolt and the lug 65 by means of a nut 70, which clamps the parts fixedly together,
50 but enables ready release of the knife by the unscrewing of the nut and the downward movement of the knife through the lower slot 71 in the foot-plate.

A shelf 74 is secured to the housing 45,
55 as by screws 75, and has an absorbent pad 76 thereon, consisting for instance of a strip of felt, which is held to the shaft by spring clips 77. This pad is provided with a slot 79, the forward end of which is narrow, so
60 that the walls thereof engage the sides of the front portion of the knife, which is exposed beyond the front edge of the standard, for wiping the same. The slot widens toward the rear end of the pad, as shown at
65 80, so as to form a lubricant receiving pocket

and fully expose the upper end of the knife-slot 23 in the standard upwardly, and form a lubricant receiving pocket.

I provide a protecting cover 83 for the crank and upper end of the pitman, and 70 form this cover as a reservoir 84 for the lubricating fluid. In the present exemplification the cover is provided with a surrounding container, comprising the double walls 85, 86, the front wall 87, and the rear wall 75 88, which latter is extended as a flange 89, by means of which the cover is secured to the casing, as by screws 90. In the present exemplification, the crank-plate and the upper end of the pitman operate within the 80 surrounding double walls of the reservoir for the lubricating fluid, the pitman operating in the lower opening 91 of the reservoir.

The lower ends of the reservoir at the respective sides of the crank and pitman are preferably connected by a connecting passage, shown as a tube 93, so that the lubricating fluid at both sides of the reservoir may find its way to the discharge passage 90 of the reservoir. The upper end of the reservoir is provided with an opening 96, adapted to be closed by a cap 97, shown as having screw-threaded connection 98 therewith, and having an air-hole 99 therein for 95 supplying atmospheric pressure in the interior of the reservoir.

One of the limbs or downwardly extending portions of the reservoir is provided with an exit-port 101, with which a tube 102 100 connects, the tube being provided with a valve 103, having a drip-nipple 104. The valve is provided with a handle 105. The valve is shown as a conical plug valve, a spring 106 between the valve-casing and a 105 pin 107 in the valve-stem continuously closely seating the valve-plug to prevent leakage of the valve.

A passage for the lubricating fluid is provided, shown in the form of a tube 110, the 110 upper end of which is shown as a funnel 111, immediately below the valve 103, but having a view-space 112 between the drip end of the valve and the funnel, so that the frequency of the dripping of the drops or the 115 flow of lubricating fluid and the sizes of the drops or stream of lubricating fluid may be readily viewed by the operator during the operation of the machine, who may at all times immediately regulate or change the 120 flow or dripping of the lubricating fluid according to the requirement of the work, with the assurance that the regulation is immediately effective, and the result of the regulation immediately observed, by reason of the 125 proximity of the valve and the viewing point of the lubricating fluid to each other and to the place of application of the lubricating fluid to the knife.

The upper part of the conducting tube 110 120

is shown mounted on a flange 114 attached to the slide housing 45 by screws 115. The tube is provided with a mouth 116 immediately above the upper end of the knife slot 23 in the standard 22, and in close proximity to the rear edge 117 of the knife. The upper end of the standard is at this point preferably provided with a rearwardly and upwardly sloping wall 119 to guide the lubricating fluid which may drip thereon to the guide-slot of the knife.

The lubricating fluid is fed to the rear edge of the knife and the rear edge of the knife-slot will, by the rapid reciprocations of the knife, and by the action of gravity, find its way throughout the length of the rear edge of the knife, so as to effectually lubricate the same, and prevent undue wear. The lubricating fluid thus fed preferably flows past the pad 76 into contact with the knife and into the knife slot.

In case of the feeding of an excess amount of lubricating fluid, which would have a tendency to damage the goods or be unclean or untidy in the workmanship, the flow or dripping of lubricating fluid may be immediately diminished, and the diminution in the flow or dripping of the lubricating fluid immediately observed, the consequent diminution of flow or dripping of lubricating fluid fed to the knife being practically instantaneous, on account of the adjacency of the valve and the viewing means to the point of application of the lubricating fluid.

My improved device is capable of a great flow and also of an extremely small flow of lubricating fluid, and of instant regulation of the flow, and provides a novel ample reservoir for the lubricating fluid, placed in novel manner, the flow of lubricating fluid being constantly within view of the operator so as to enable the operator to continually control the same.

If it is desired to supply sufficient amount of lubricating fluid to lubricate the front portion of the knife, as when cutting certain fabrics, for instance rubberized or leatherized fabrics, the dripping or flow of lubricating fluid may be increased to cause the lubricating fluid to exude between the walls of the knife-slot and the knife-blade into contact with the exposed portion of the knife-blade and with the fabric being cut. If desired, the flow may be increased sufficiently to saturate the absorbent pad 76, whereby a film of lubricating fluid is continuously supplied to the exposed portion of the knife. The passage between the funnel and the knife-slot is readily cleaned. The pad is readily replaced by simply raising the spring clips 77 and substituting a different pad.

By means of my improved device a reservoir of large capacity is provided in a position which will not interfere with the opera-

tion of the machine or the viewing of its operations, the reservoir acting as a protection for the operative connections between the crank and the pitman. In the exemplification, the reservoir and the drip-valve 70 are located in substantially the longitudinal projection of the motor-casing, to accomplish the ideas of convenience and compactness of structure, the arrangement of the parts also minimizing the danger of injury 75 to or breakage of the parts.

Having thus fully described my invention, what I claim as new, and desire to secure by Letters Patent, is:

1. In a cloth cutting machine, the combination of a rotatable driving part, a reciprocating knife located lower than said driving part, a pitman connection between said rotatable driving part and said knife, a protective casing for said pitman connection 80 comprising a reservoir for lubricating fluid located higher than said reciprocating knife, and conducting means for the lubricating fluid for said knife leading from said reservoir, said conducting means comprising a 85 viewing part for the lubricating fluid located at the front part of the machine proximate to the upper end of said knife so as to be within the view of the operator while operating the machine. 95

2. In a reciprocating knife cloth cutting machine, the combination of an operating crank, a pitman having operative connection therewith, said pitman having operative connection with the reciprocating 100 knife, a lubricant reservoir having a double horse-shoe shaped wall received about the path of said crank and having an opening between the lower ends of the limbs of said double horse-shoe shaped wall, said lower 105 ends presented downwardly, said pitman projecting through said opening, and a lubricant feeding duct between said reservoir and said knife.

3. In a reciprocating knife cloth cutting 110 machine, the combination of an operating crank, a pitman having operative connection therewith, said pitman having operative connection with the reciprocating knife, a lubricant reservoir having a double 115 horse-shoe shaped wall received about the path of said crank and having an opening between the lower ends of the limbs of said double horse-shoe shaped wall, said lower 120 ends presented downwardly, said pitman projecting through said opening, a connecting lubricant passage between said lower ends of said limbs, and a lubricant feeding duct between said reservoir and said knife. 125

4. In a reciprocating knife cloth cutting machine, the combination of an electric motor comprising an armature-shaft, a crank driven by the latter, a reciprocating slide to reciprocate the knife, a pitman connect- 130

ing said crank and said slide, a reservoir for lubricating fluid protectingly located at said crank, and feeding and regulating means for the lubricating fluid between said reservoir and the reciprocating knife, said last-named means comprising visual drip means for the lubricating fluid and receiving means therefor, said visual drip means and said receiving means relatively stationary positioned near the knife within the view of the operator while operating the machine.

5. In a reciprocating knife cloth cutting machine, the combination of a foot-plate, a narrow standard rising therefrom, an electric motor supported by said standard, said standard having a guideway for the reciprocating knife, crank and pitman means for reciprocating said knife having connection 10 with said electric motor for being driven thereby, a reservoir for lubricating fluid protectingly received about said crank and pitman means, a passage for lubricating fluid from said reservoir to direct flow of lubricating fluid to said knife and said guideway, a regulating valve therefor, and viewing means near said knife for said lubricating fluid between said valve and said knife.

6. In a cloth cutting machine the combination of a knife-standard, a crank at the upper end thereof, a pitman for reciprocating the knife in said standard, said pitman having operative connection with said crank, and a pluri-walled protective casing 30 about the path of said operative connection, said pluri-walled protective casing forming a reservoir for a lubricant for the knife, and a lubricant passage between said reservoir and said standard.

40. 7. In a cloth cutting machine, the combination of a knife standard, a motor mounted thereon, a crank operated by the motor, a pitman having operative connection with said crank, a lubricant reservoir about the path of said operative connection, a reciprocating knife with which said pitman has

connection for reciprocating the same, said lubricant reservoir having depending portions at the respective sides of said pitman, a connecting passage between said depending portions for connecting the same, said connecting passage extending cross-wise of the path of said pitman at both sides of said pitman, a lubricant passage for directing the lubricant to the knife, and a feeding control for said passage.

8. In a cloth-cutting machine, the combination of a knife-standard, said standard provided with a knife-slot, a pad at the upper end of said knife-slot, said pad provided with a slot in which the knife reciprocates, the rear portion of said last-named slot being wider than said knife-slot for forming a lubricant receiving pocket at the upper end of said knife-slot, a reservoir for said lubricant, and a passage therefrom having a discharge opening in adjacency to said knife-slot and to said rear lubricant receiving pocket portion of said slot in said pad.

9. In a cloth-cutting machine, the combination of a knife-standard provided with a knife-slot, a motor on said standard, a reservoir for lubricating fluid for lubricating the knife, a drip-valve therefor, a funnel spaced 75 from said drip-valve into which said drip-valve discharges, and a passage between said funnel and said knife-slot, said drip-valve, said funnel and the space between said drip-valve and said funnel located at 80 the front of the machine at the upper end of said knife-standard, and said space presented to view of the operator while operating the machine.

In testimony wherof, I have hereunto signed my name in the presence of two subscribing witnesses.

HENRY A. MEYER.

In presence of—

JAMES J. FITZPATRICK,
DELMA WERNING.
